Primary Examiner — Jonathan J Han*Assistant Examiner* — Caitlin Mackenzie Williams(74) Attorney, Agent, or Firm — Cook Alex Ltd.(57) CLAIM

The ornamental design for a footwear upper as shown and described.

DESCRIPTION

FIG. 1 is a perspective view of a footwear upper embodying the new design; and,

FIG. 2 is a right side view thereof.

The dot-dot-dash broken lines in FIGS. 1-2 show portions of an article of footwear that form no part of the claimed design. The even length broken lines in the figures depict stitching, which forms no part of the claimed design.
